UNITED STATES PATENT OFFICE.

JOHN H. CHIDLLOW, OF CUT BANK, MONTANA.

FIRE-BOX DOOR AND DEFLECTOR PLATE.

Application filed March 14, 1924. Serial No. 699,228.

To all whom it may concern:

Be it known that I, JOHN H. CHIDLLOW, a citizen of the United States, residing at Cut Bank, in the county of Glacier and State 5 of Montana, have invented certain new and useful Improvements in Fire-Box Doors and Deflector Plates, of which the following is a specification.

This invention relates to improvements in fire box doors particularly adapted to be used on steam boiler furnaces of the oil-burning type.

An important object of the invention is to provide a fire box door which will permit more efficient combustion in the fire box.

A further object of the invention is to provide an apparatus of this character which has a detachable draft box mounted thereon, thereby permitting better control of the draft fed into the fire box.

A still further object of the invention is to provide an apparatus of this character which is comparatively simple yet durable in construction and efficient for the purpose intended.

Other objects and advantages of this invention will be apparent in the course of the following description.

In the accompanying drawings forming a part of this specification and in which like numerals are employed to designate like parts throughout the same:

Figure 1 is a front elevation of my improved apparatus mounted on the front of a fire box,

Figure 2 is a top plan view of the same,

Figure 3 is a vertical transverse section taken on the line 3—3 of Figure 1, and

Figure 4 is a horizontal sectional view.

In the drawings, wherein for the purpose of illustration is shown the preferred embodiment of my invention, the numeral 5 denotes the front of a fire box which may be mounted upon any steam boiler, but is particularly adapted for use on locomotives. The front of the fire box 5 has an opening 6 formed therein for the purpose of mounting a fire door generally denoted by the numeral 7 thereon.

The fire door which is composed of a door frame 8 substantially oval in form and adapted to close the opening formed in the fire box is provided with a pair of extension hinged members 9 on one side thereof so positioned upon the door frame as to engage a pair of hinged supports 10 secured to the

fire box and connected to the hinged members 9 by means of the hinge pins 11 thereby permitting the door to be swung in a horizontal plane.

The baffle plate or deflector 12 is mounted on the rear of the door frame 8 and is hingedly connected thereto by means of a pair of extension pins 13 formed on the extremities of the upper edge, rotatably mounted within a pair of sockets 14 secured to the door frame. The upper extremity of the baffle plate 12 has an angular bracket 15 formed in the center thereof, an opening 16 being formed near the upper edge to allow an adjustment screw 17 to be inserted therethrough, the adjustment screw being threadedly mounted through an internally threaded opening formed near the upper extremity of the door frame. As the baffle plate 12 is to be swung about the pivot pins 13 I provide an annular collar 18 which is positioned upon the adjustable screw 17 on the inner side of the baffle plate thereby permitting the angular extension 15 to be moved inwardly.

The outer side of the door frame 8 has a pair of vertical flange strips 19 welded or otherwise secured thereon with a solid connecting strip 20 formed on the lower portion comprising a retaining frame for a draft box generally denoted by the numeral 21 which has a pair of flange members 22 formed on the sides thereof adapted to slide in suitable grooves formed by the flange strips 19. The front of the draft box 21 is inclined toward the fire box at the upper extremity as denoted by the numeral 22', the rear being open and connecting with the front face of the door frame. The bottom 23 of the fire box is pivotally connected thereto by a pair of pivot pins formed on the extreme side adapted to engage suitable openings formed in the sides of the box 21. As it is intended to lower the bottom 23 in order to supply sufficient draft to the fire box I provide a hinged regulating rod 24 which is hingedly connected to a bracket 25 formed on the upper side of the bottom and provided with an opening to receive the angular extension upon the rod 24. The rod 24 is adapted to extend through an opening formed in the inclined front portion of the draft box and carries a collar 26, fitted about the rod, and retained in various positions thereon by means of a thumb screw 27 which is threadedly mounted in the collar

26 and engages the rod 24, thereby enabling the bottom to be set at any angular position desired.

A conventional type of latch 28 is hinged-
ly connected with the extremity of the door frame and is adapted to engage a suitable lug 29 formed on the fire-box front, permitting the door to be tightly closed.

In use, my improved door may be used
10 with the draft box attached thereto if desired thus allowing the draft fed to the fire box to be controlled. It is also obvious that the baffle plate or deflector 12 may be regulated to any angular position desired to permit more complete combustion of the fuel. When it is found desirable to remove the draft box 21 which may be readily accomplished as illustrated in the drawings, it is first necessary to remove the adjustment
15 screw 17 in order that the draft box may be forced upwardly and removed from the retaining strip.

It is to be understood that the form of my invention herewith shown and described
20 is to be taken as the preferred example of the same, and that various changes as to the shape, size and arrangement of parts may be resorted to without departing from

the spirit of the invention, or the scope of the subjoined claim:

Having thus described my invention, I claim:

A fire box door structure comprising a door panel provided with an opening, wide flanges provided at one side of the door 30 and extending around three edges of the opening; a draft hood fitting in the flanges, said hood having an adjustable bottom panel, the door panel being provided at its opposite sides and at the upper edge of the 35 opening with sockets; a baffle plate having pins which enter the socket, said plate being normally disposed over the opening in the panel and with its lower edge spaced above the lower edge of the opening, the 40 plate being provided at its upper portion with an offset bracket, and a screw passing through the door panel above the opening thereof and connected at its inner end with the offset bracket of the baffle plate, the 45 outer end portion of the screw being disposed above the hood and above the ends of the guide flanges which retain the hood.

In testimony whereof, I have affixed my signature.

JOHN H. CHIDLLOW.
